PLATE TRAY

Clement J. Smith, 1512 Tralle St.,
Houston, Tex. 77020

Filed Apr. 19, 1973, Ser. No. 352,526

Term of patent 14 years

Int. Cl. D7—99

U.S. Cl. D7—37

FIG. 1 is a top front perspective view of a plate tray in its upright position showing my design;

FIG. 2 is a bottom rear perspective view of the plate tray shown in FIG. 1, inverted through an arc of 180°.

I claim:

The ornamental design for a plate tray, as shown.
